UNITED STATES PATENT OFFICE.

PAUL L. COOK, OF CHATTANOOGA, TENNESSEE.

UMBRELLA.

1,394,408.

Specification of Letters Patent.

Patented Oct. 18, 1921.

Application filed September 20, 1919. Serial No. 325,231.

To all whom it may concern:

Be it known that I, PAUL L. COOK, a citizen of the United States, residing at Chattanooga, in the county of Hamilton and State of Tennessee, have invented certain new and useful Improvements in Umbrellas; and I do hereby declare the following to be a full, clear, and exact description of the invention, such as will enable others skilled 10 in the art to which it appertains to make and use the same.

My invention relates to improvements in umbrellas of the folding type.

An important object of this invention is 15 to provide novel means for folding an umbrella within a small space without tearing or straining the cover of the same.

A further object of the invention is to 20 provide means for quickly and conveniently folding the umbrella to permit the same to be carried in valises or stored in other small places.

A further object is to provide an umbrella 25 of the character described, which is cheap, few in parts and neat in appearance.

Other objects and advantages will be apparent during the course of the following description.

In the accompanying drawings forming 30 a part of this application and in which like numerals are employed to designate like parts throughout the same,

Figure 1 is a side elevation of the frame of my improved umbrella open,

Fig. 2 is a side elevation of the frame folded,

Fig. 3 is a side elevation of the umbrella partly folded, the cover being shown in section,

Fig. 4 is a detail perspective of the folding ribs, and associated elements, and,

Fig. 5 is a fragmentary side elevation of umbrella staff folded, parts being shown in section.

In the drawings wherein for the purpose of illustration is shown a preferred embodiment of my invention, the numeral 10 generally designates an umbrella staff or main rod including a pair of sections 12 and 13. A handle 14 of any desired type is arranged on the section 13. As indicated the forward end of the section 13 is provided with a screw threaded extension 15 adapted to partake of threaded engagement with the interior of the section 12. A link 16 is connected to the extension 15 and is also pivotally connected

to a rod 17 slidably arranged in the tubular section 12. A cylindrical member 18 slidably mounts the rod 17 and a head 17' is formed on said rod 17 to prevent accidental detachment thereof from frame through the cylinder 18. When the extension 15 has threaded engagement with the tubular section 12, the sections 12 and 13 are rigidly connected. The staff proper is provided with an annulus 19 at its forward end portion. The annulus 19 has pivotal connection with a plurality of pivoted ribs 20. As indicated in Fig. 4 the outer end portions of the ribs 20 are provided with cylindrical sleeves 21, having openings 22 slidably receiving ribs 23. The ribs 23 for the purpose of this discussion will be designated slidable ribs, while the ribs 20 will be designated main or pivoted ribs. The slidable ribs 23 are connected at their outer 75 ends to a cover 24. The central portion of the cover 24 is secured to the annulus 19 as is usual. A sleeve 25 is rigidly secured to the inner end portion of each slidable rib 23 and is provided with an opening 26 slidably 80 receiving the adjacent ribs 20. With reference to Fig. 2, it will be noted that the slidable ribs 23 may be slid under the ribs 20 when it is desired to fold the umbrella.

A runner 27 of any desired construction 85 is arranged on the staff 10 and has pivotal connection with a plurality of stretchers 28.

As indicated in Fig. 4 the outer end portions of the stretchers 28 are provided with forked arms 29 having pivotal connection 90 with the sleeve 25 as indicated at 30. The cover 24 is secured between its central portion and its outer edge to the sleeves 25 as indicated at 31.

When it is desired to fold the umbrella, 95 the runner 27 is drawn down as usual and the umbrella caused to assume the usual closed position. The slidable ribs 23 are now drawn upwardly alongside of the ribs 20 and the cloth covering arranged over the 100 slidable ribs 23 caused to fold under the cloth arranged over the main or pivoted ribs. The section 13 may now be folded as indicated in Fig. 3 and the umbrella will occupy but a minimum of space.

When it is desired to open the umbrella, 105 the sections or ribs 23 are caused to assume an extended position with relation to the ribs 20 and the runner 27 subsequently forced upwardly, for opening the umbrella cover. 110

While I have shown and described the preferred embodiment of my invention, it is

understood that I may make such minor changes in arrangement and construction of parts as will remain within the spirit of the invention and the scope of the appended 5 claims.

Having thus described my invention, what I claim is:—

1. A folding umbrella having a rib in relatively movable sections, a block fixed to 10 each section and slidably mounting the complementary section, a cover secured to one of the sections and to the block thereon, a stretcher having a bifurcated portion, and the last mentioned block being disposed in 15 said portion and braced thereby against axial movement, and means to pivot the last mentioned block to the stretcher.

2. A folding umbrella having a rib in relatively movable sections, a block fixed to

each section and slidably mounting the complementary section, a cover secured to one of the sections and to the block thereon, a stretcher having a bifurcated portion, and the last mentioned block being disposed in 20 said portion and braced thereby against axial movement, and means to pivot the last mentioned block to the stretcher, the said section being disposed in vertical alinement and the pivot means engaging such block intermediate the transverse planes of the sections. 25

In testimony whereof I affix my signature in presence of two witnesses.

PAUL L. COOK.

Witnesses:

LEIGHTON P. COOK,
Mrs. LEIGHTON P. COOK.
